CLAIM

The ornamental design for a portable medical monitor mount, as shown and described.

DESCRIPTION

FIG. 1 is a front perspective view of a portable medical monitor mount showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a bottom view thereof; and,

FIG. 8 is a top view thereof.

The broken lines consisting of uniformly-sized dashes depict portions of the portable medical monitor mount that form no part of the claimed design. The broken lines consisting of lone and short dashes define the boundary of the claim, which extends to the boundary but does not include the boundary.
